(57) **CLAIM**

The ornamental design for a loudspeaker housing, as shown and described.

DESCRIPTION

FIG. 1 is a perspective view of a loudspeaker housing showing our new design;

FIG. 2 is top plan view thereof;

FIG. 3 is a front elevational view thereof;

FIG. 4 is a rear elevational view thereof;

FIG. 5 is an end elevational view thereof, shown rotated from the orientation in FIG. 1;

FIG. 6 is another perspective view thereof in an orientation that is rotated forward of the orientation of FIG. 1;

FIG. 7 is another perspective view thereof in a vertical orientation; and,

FIG. 8 is an elevational view thereof in a vertical orientation. The orientation illustrated in FIGS. 1-4 is a possible horizontal orientation during use. As evident from the end view, FIG. 5, the claimed loudspeaker has seven sides and the loudspeaker may be rotated such that any side may serve as a base as illustrated in FIGS. 5 and 6. The orientation illustrated in FIGS. 7-8 is a possible vertical orientation during use. The broken lines shown are included for the purpose of illustrating the unclaimed portions of the article and form no part of the claim.
